CLAIM

The ornamental design for an infant car seat, as shown and described.

DESCRIPTION

FIG. 1 is a perspective view of an infant car seat showing my new design;

FIG. 2 is a right side view thereof;

FIG. 3 is a left side view thereof;

FIG. 4 is a front end view thereof;

FIG. 5 is a rear end view thereof; and,

FIG. 6 is a top plan view thereof.

The broken line showing is for illustrative purposes only and forms no part of the claimed design.
